UNITED STATES PATENT OFFICE.

JACOB OFMAN, OF ROTTERDAM, NETHERLANDS.

COOKING-STOVE.

1,306,435.

Specification of Letters Patent. Patented June 10, 1919.

Application filed March 4, 1919. Serial No. 280,658.

To all whom it may concern:

Be it known that I, JACOB OFMAN, teacher, subject of the Queen of the Netherlands, residing at Rotterdam, the Netherlands, have 5 invented certain new and useful Improvements in Cooking-Stoves, of which the following is a specification.

The present invention relates to cooking stoves, the stove according to my invention 10 requiring less fuel for a given capacity of food to be prepared than the stoves heretofore known.

According to the present invention, the fire-place arranged underneath the oven 15 space is provided with a rotary slide for equally dividing the combustion gases, conduits being provided for these gases which pass through or near the oven space and are connected above the latter with a chimney flue. Preferably this rotary slide forms a part of a rotary cylinder forming a jacket around the furnace or a part thereof, this cylinder being provided with holes which may be made to register with holes provided 20 in an outer jacket. In this way the combustion gases are equally divided over the smoke conduits connected with the holes arranged in said outer jacket, independent of the fact that the draft wholly or partly 25 exerts its influence. The rotation of the inner jacket or the furnace may also be utilized for opening or closing the stoke hole. A separate fire door is hence superfluous.

A cooking hole in the bottom of the oven 30 arranged centrally above the furnace is wholly exposed to the action of the narrow flames in consequence of the equal exit of combustion gases in different directions through the rotary slide. In ordinary cooking stoves on the contrary the flames exit 35 together in an inclined direction so that but a small part of the bottom of the cooking pan is in direct contact with the gases. The equal division of the combustion gases on a 40 certain number of fire holes is thus exceedingly advantageous for a quick and hence economical heating of the cooking pan.

Apart from the equal division of heat on the oven the rotary slide has the following 45 effect.

If the slide holes are wide open and if thus the draft exerts its full influence the combustion takes place past the slide holes, the combustion space having thus a great 50 capacity. Of course the fire must have a corresponding intensity. If on the contrary

the passages are reduced, the combustion space is limited to the space situated directly above the fire. With a small fire a much more effective combustion is obtained in 55 this way than in case the fire were maintained in a large space. The rotary slide contributes thus to a great extent to an economical fuel consumption. This advantage is still increased by the natural insulating and preheating of air obtained by 60 means of the double wall consisting of the rotary slide and the jacket.

The combination of the rotary stoke hole and the rotary slide obliges the user of the 65 cooking stove to learn the function of the rotary slide in consequence of which the latter is effectively used. The slide can neither be neglected nor immobilized by dirt. The contrary case too often presents itself 70 with cooking apparatus whose complication renders their use incomprehensible to most users. The vertical slot between the rotary slide and the jacket and the repeated relative displacement of these parts during the 75 stoking process prevents these parts from becoming immobilized by grit.

The equal division of heat over the oven space allows of keeping boiling food in boiling condition in any part of said space. 80 There may be provided adjustable rings on standards for receiving pans or other cooking utensils one above the other so that it is possible to arrange within a space of rather restricted dimensions a relatively great number of pans which may be separately controlled.

The accompanying drawings represent one embodiment of the cooking stove according 85 to my invention.

Figure 1 represents a front view and Fig. 2 a vertical section of the cooking 90 stove,

Fig. 3 is a horizontal cross-section on the fire holes, seen from above and without the 95 furnace.

Fig. 4 is a cross section of the same kind, the different parts occupying a different position with regard to one another, the furnace being shown without the grate.

Fig. 5 is a horizontal cross section of the 100 stove seen from above.

The grate 6 is arranged within an ordinary furnace 7 the latter being suspended within a cylinder 8. This cylinder contains 110 in its lower part an ash tray 9, and its bottom rests by means of an extension 10 in a

rotatable manner on a bearing plate 11 spread out on the floor.

The upper part of the cylinder 8 is provided with fire holes 12 which can be made 5 to register with fire holes 13 in an outer cylinder or jacket 14. The position of the holes 12 with regard to the holes 13 may be adjusted by rotating the cylinder 8, the latter being provided for this purpose with a 10 handle 15 which may be caught with a poker or a fire hook. A pointer provided on said handle and marks on the jacket 14 indicate the grade of regulation (Fig. 1).

The cylinder 8 is provided with a stoke 15 hole arranged opposite the feed opening 16 of the furnace and the mantle 14 is provided with a stoke hole 17. By rotating the cylinder both stoke holes can be made to register. When the fuel is introduced some 20 of the fire holes 12 and 13 still present such a passage as to maintain a sufficient draft. Fig. 4 shows the way in which the feed opening 16 is brought in front lying then opposite the stoke hole 17 (compare Fig. 1). 25 The flange of the furnace 7 is provided with recesses 18 so that a small quantity of air can pass along the outside of the furnace and join the combustion gases through the openings 18. This very hot air produces an 30 intense smoke combustion and adds moreover to the heating of the oven 19. The latter is provided with a double wall and with a door 20 having a vapor hole 21. The oven is heated by the flues 22 connected with 35 the holes 13 and communicating at the upper part of the oven with the chimney piece 23.

Copies of this patent may be obtained for five cents each, by addressing the "Commissioner of Patents, Washington, D. C."

The oven is insulated at its circumference so that the heat losses are limited to a minimum. The jacket 14 may also be 40 provided with an insulation.

It is obvious that with a cooking stove of larger dimensions a greater number of cooking holes may be provided in the bottom of the oven space. These holes are then swept 45 by the gases or flames on their way from the fire holes 13 to the fire tubes 22.

I claim as my invention:

1. In a cooking stove, the combination 50 with the chimney, of an oven, a fire-place underneath the same, a number of open flues extending along the said oven and connected with the chimney above the oven, a cylindrical jacket depending from the bottom of said oven, and a rotatable cylinder surrounding said fire-place and having apertures adapted to register with similar apertures in the said cylindrical jacket upon the rotation of the said cylinder. 55

2. A cooking stove, as specified in claim 1, 60 comprising a rotary cylinder provided with a stoke-hole adapted to register with a stoke-hole in said jacket upon the rotation of said cylinder through a certain angle, preferably of 90 degrees. 65

3. A cooking stove, as specified in claim 2 comprising a flange provided on the upper end of the fireplace contained in said rotary cylinder, the said flange having recesses so arranged as to permit heated air to join the 70 gases of combustion.

In testimony whereof I affix my signature.

JACOB OFMAN.
